WATER FOUNTAIN

Filed Nov. 16. 1928

Reuben Kielesmeier,
INVENTOR

BY *Victor J. Evans*

ATTORNEY

William Thompson

WITNESS:

UNITED STATES PATENT OFFICE

REUBEN KIELSMEIER, OF BALDWIN PARK, CALIFORNIA

WATER FOUNTAIN

Application filed November 16, 1928. Serial No. 319,917.

This invention relates to improvements in valve structures embodying among other characteristics means for automatically opening and closing same.

5 An object of the invention comprehends a supporting arm for the valve operating block.

Another object of the invention contemplates a spring element adapted to yieldingly 10 position the supporting arm in proper position.

An additional object of the invention consists in the provision of an operating lever carried upon the supporting arm and adapted 15 to actuate the block to unseat the valve.

More specifically stated the supporting arm is provided with adjusting elements whereby the block may be supported in such positions that the operating lever will reciprocate the block to actuate the valve member when desired.

With the above and other objects in view, the invention further consists of the following novel features and details of construction, to be hereinafter more fully described, 25 illustrated in the accompanying drawings and pointed out in the appended claims.

In the drawings:—

Figure 1 is a longitudinal sectional view 30 taken through my invention.

Figure 2 is a view similar to Figure 1 with the water pipe removed and the valve disclosed in open position pursuant to the active position of the operating lever.

35 Figure 3 is a rear elevation of the invention.

Figure 4 is a bottom plan view of the invention.

40 Figure 5 is a front elevation of the invention with certain of the parts removed.

Referring to the drawings in detail where-in like characters of reference denote corresponding parts, the reference character 10 indicates a casting for a valve member having inlet and discharge bores 11 and 12 communicating through a passage 13. The bottom wall of the inlet bore 11 about the communicating passageway 13 provides a valve seat 14 for a valve member 15 having the stem 16 therefor extended through the passage 13.

A block 17, mounted for reciprocating action within the discharge bore 12, is adapted for engagement with the lowermost depending end of the valve stem 16.

A supporting arm, such as indicated at 18, pivoted upon a cotter pin 19 passed through the registering apertures in spaced ears 20 rearwardly projected from the valve body or casting 10, is adapted to support the block 17 upon the upper side edge thereof in the manner shown in Figure 1 of the drawing. An extension or arm, such as indicated at 21, including an aperture 22 within its outermost end is adapted to accommodate a loosely fitting screw threaded shaft 23 having an adjusting nut 24 upon its uppermost end and reposing upon the upper side of the supporting arm 21. A retractile spring 25, having connection at its lowermost end adjacent the outermost extremity of the supporting arm 18, is adapted for connection at its opposite end with a ring 26 formed within the lowermost depending end of the screw threaded shaft 23.

A fin 27, projected in parallelism with the extension or arm 21, receives a vertically disposed set screw 28 having contacting engagement at its lowermost end with the upper side edge of the supporting arm 18 whereby the clearance between the upper end of the block 17 and the lowermost depending end of the valve stem 16 may be regulated exteriorly of the valve body or casting 10 and against the tension of the spring 25.

A set screw 29, adjustably mounted within the bottom of the casting 10 and to one side of a slot 30 therein adapted to permit projection of the supporting arm 18, is adapted to engage the under side edge of the supporting arm 18 to restrict downward movement thereof. A water pan 31, supported at one end upon legs 32, preferably arranged upon a ledge or shelf 33 at an appreciable height upon a wall structure 34, carries a bail or handle 35 upon the upper side of its opposite end.

The yoke portion of the bail or handle is in turn adapted for reception within a cut-out portion 36 in the upper side and adjacent the outermost extremity of the supporting 100

arm 18, substantially as illustrated in Figure 2 of the drawings.

An operating lever 37, pivotally and eccentrically mounted, as at 38, upon the supporting arm 18, is adapted to dispose the innermost end thereof immediately beneath the end of the block 17 supported upon the upper side edge of the arm 18. The outermost end of the operating lever being extended in parallelism with that of the supporting arm 18 adjacent the notch 36 to project beneath and frictionally engage the bail or handle 35 for the receptacle or pan 31.

The weight of the receptacle or pan 31 in and of itself is sufficient to shift the operating lever 37 upon its pivot to contact with the block 17 to open the valve 15 as illustrated in Figure 2 of the drawing. This will start the water flowing from the valve body or casting 10 into the receptacle. When the receptacle has been nearly filled, its added weight will overcome the tension of the retractile spring 25 upon the supporting arm 18 and lower it to the head of the set screw 29. This movement will be sufficient to release the block 17 from engagement with the valve stem 16 whereby the valve member 15 will close by water pressure.

When a suitable quantity of the water in the pan or receptacle 31 has been drunk or evaporated, the spring 25 will then be called into use to retract the arm 18 to occupy the positions shown in Figures 1 and 2 of the drawing, but the operating lever 37 will always remain in the Figure 2 position whereby the valve 15 will again become unseated and the receptacle or pan 31 will be constantly filled to a predetermined level.

Obviously the block 17 is of such weight as to cause constant contacting engagement of the upper side edge of the operating lever with the inner side of the yoke portion for the bail or handle 35.

When it is necessary to remove the pan or receptacle for cleaning or other purposes the bail is removed from the notch in the end of the supporting arm 18 and the operating lever 37 will then occupy the Figure 1 position to liberate the block 17 from the valve. The pressure of the water against the valve 15 will automatically cut off the water supply.

The invention is susceptible of various changes in its form, proportions and minor details of construction, and the right is here reserved to make such changes as properly fall within the scope of the appended claims.

Having thus described the invention, what is claimed is:—

1. An automatic valve comprising a valve body having inlet and exhaust ports at its ends, a valve member carried within the inlet port, said body having a communicating passage between the ports, a stem for the valve extending through the passage into the

exhaust port, a block mounted within the exhaust port, a movable arm adapted to retain the block in juxtaposition to the stem, an operating lever carried by the arm to actuate the block to unseat the valve, and a water pan suspended from the lever for actuating the lever and adapted to move said arm when the lever is moved a predetermined amount to permit seating of the valve.

2. An automatic valve comprising a valve body having inlet and exhaust ports at its ends, a valve member carried within the inlet port, said body having a communicating passage between the ports, a stem for the valve extending through the passage into the exhaust port, a block mounted within the exhaust port, a movable arm adapted to retain the block in juxtaposition to the stem, an operating lever carried by the arm to actuate the block to unseat the valve, means carried by the valve body for yieldingly retaining the arm in position for use, and a pan suspended from the lever for actuating the lever and adapted to move said arm when the lever is moved a predetermined amount to permit seating of the valve.

3. An automatic valve comprising a valve body having communicating inlet and exhaust ports within its ends, a stemmed valve arranged within the inlet port and having the stem therefor projected through the communicating passage into the exhaust port, an arm pivotally mounted at one end upon the valve body adjacent the exhaust port, a block mounted for reciprocating action within the exhaust port and normally seated upon the adjacent portion of the arm, spring means carried adjacent the opposite end of the arm and having adjustable connection with the valve body, an operating lever pivotally and eccentrically mounted upon the arm being adapted for operative engagement with the block, and a pan suspended at one end from the lever for actuating the lever and adapted to move said arm against the tension of said spring when the lever is moved a predetermined amount to permit seating of the valve.

4. An automatic valve comprising a valve body having communicating inlet and exhaust ports within its ends, a stemmed valve arranged within the inlet port and having the stem therefor projected through the communicating passage into the exhaust port, an arm pivotally mounted at one end upon the valve body adjacent the exhaust port, a block mounted for reciprocating action within the exhaust port and normally seated upon the adjacent portion of the arm, spring means carried adjacent the opposite end of the arm and having adjustable connection with the valve body, means for regulating the position of the arm, an operating lever pivotally and eccentrically mounted upon the arm being adapted for engagement at one end with the block to unseat the valve, and a pan

suspended at one end from the lever for actuating the lever and adapted to move said arm against the tension of said spring when the lever is moved a predetermined amount to permit seating of the valve.

5. An automatic valve comprising a body having inlet and exhaust ports adjacent its ends communicating through a central passage, a stemmed valve arranged within the 10 inlet port and seated against the bottom wall thereof and having the stem therefor projecting through the communicating passage within the exhaust port, an arm pivotally mounted at one end upon the body and having 15 the upper side edge thereof disposed adjacent the mouth of the exhaust port, a block mounted for reciprocating action within the exhaust port and seated upon the adjacent portion of the arm, set screws carried by the body and 20 adapted to engage the opposite side edges of the arm to regulate pivotal swinging movement thereof, an adjusting shaft mounted upon the body, a retractile spring establishing the means of connection between the 25 outermost end of the arm and the adjacent end of the adjusting shaft, an operating lever pivotally and eccentrically mounted upon the arm being adapted for contacting engagement at one end with the block to unseat the 30 valve within the inlet port, and a pan suspended at one end from the lever for actuating the lever and adapted to move said arm against the tension of said spring when the lever is moved a predetermined amount to 35 permit seating of the valve.

In testimony whereof I affix my signature.
REUBEN KIELSMEIER.
